United States Patent Office.

A. W. PERRY, OF ST. JOSEPH, MISSOURI.

Letters Patent No. 97,686, dated December 7, 1869.

IMPROVEMENT IN PIANO-FORTE ACTION.

The Schedule referred to in these Letters Patent and making part of the same.

To all whom it may concern:

Be it known that I, A. W. PERRY, of St. Joseph, in the county of Buchanan, and State of Missouri, have invented a new and improved Piano-Action; and I do hereby declare that the following is a full, clear, and exact description of the construction and operation of the same, reference being had to the accompanying drawings, making a part of this specification, in which—

Figure 1 is a side view, representing the position of the several parts, just as the hammer is dropping from the lip of the back-catch, and

Figure 2 is a similar view, representing the position of the parts at the instant that the hammer touches the string.

The object of this invention is to so construct and arrange the several parts composing the action, that in playing passages where the same note is repeated with great rapidity, the whole passage can be played so as to bring out the individual notes with the utmost distinctness, delicacy, and perfection of tone, by an exceedingly slight and rapid depression of the key.

To this end, the action is so constructed as to return the movement to position for a repeating blow before the key-lever returns to its cushion. At the same time the use of the hammer-rail is avoided, and the weight of the hammer, stem, and their appendages, is made to bear absolutely upon the key-lever, at all times, and in every position.

The combinations that effect this result are simple in construction, certain of operation, capable of being adjusted and regulated with the utmost, nicety, and not liable to derangement or injury from the careless or improper use of the instrument.

In the drawings—

A is the key-lever, pivoted at a , so that the inner end will slightly overbalance the outer, and provided with the usual cushions a^1 a^2 .

B is a fulcrum, supported in a gain, on the upper side of the key-lever, near its inner end, and capable of being adjusted longitudinally upon its supporting-lever by means of a set-screw or other suitable appliance:

C is an oscillating lever, pivoted at its centre upon the fulcrum B, so that when rocked, its ends will drop upon cushions c c' , attached to the upper side of the key-lever.

D is the back-catch, attached, by a stem, d , to the rear end of lever C, and formed as represented in the drawing, being provided with a cushion, e , and a nearly horizontal lip, e' , on its front side, at right angles with the cushion.

e^2 is the but of lever C, upon which the foot of the jack operates during a portion of the movement, it being slightly bevelled or rounded, and covered with

leather, to allow said foot to pass on to and off from it without catching, and with easy, ready action.

E is the stationary but, attached to the upper side of the key-lever by means of screws i i , and resting on a fulcrum, i' , so that by adjusting the screws it can be fixed in the proper position with relation to the lever-but, its inner end being also rounded off on the upper edges, and covered with leather, for the purpose, above described, in connection with the but c^2 .

F is the hammer.

G, the hammer-stem, articulated at g to the flanch H, supported by the flanch-rail I.

J is the jack, articulated at j to the hammer-stem, near the flanch, and when the hammer is in contact with the string K, hanging vertically, with its lower end resting upon both C and E, as shown in fig. 2.

L is an arm, projecting at right angles from the front side of the jack, and extending under the flanch-rail.

l is a vertically-adjustable cushion, attached to the under side of the flanch-rail, for the arm L to act against, and, as it is adjusted higher or lower, capable of limiting and controlling the movement of the arm L and the jack.

m is a cushioned stop, supported by a rail, M, and vertically adjustable, for the purpose of limiting the movement of lever C.

n, a cushioned stop, supported by a post attached to but E, and horizontally adjustable, its function being to limit and control the movement of the jack, as will be clearly understood from the drawings; and

S, a spiral spring, connecting the flanch and front side of the jack, for the purpose of drawing the latter forward against stop n, as hereinafter described.

The action of the several parts above specified is as follows:

The key-lever, when not in use, rests upon fulcrum a and cushion a^2 , the lower end of the hammer being nearly down to the lever C, the latter resting upon the points B c , the jack resting upon the but E, and against stop n, as shown in fig. 1, and the arm L being separated from stop l, as shown in the same figure.

If, now, the key be depressed so as to throw the hammer against the string, lever C will, at the instant that the string is touched, be brought in contact with stop m, and its but c^2 depressed below the edge of but E, so that the jack can step over upon it, while the arm L will strike stop l and throw the foot of the jack off of but E upon but e^2 .

The lower end of the hammer will then drop back upon the cushion e , and slide over the lip e' , until, as the key-lever returns toward its original position, the parts C E reach the relative positions shown in fig. 2, when the foot of the jack will be drawn forward upon but E by the combined operation of but e^2 and

spring S, relieving lever C, and the weight of the back-catch will throw lever C into the position shown in fig. 1, and allow the hammer to drop to its original position, above described. When in this position, the but c' projects above the lower end of the jack, serving to confine the latter upon the end of but E until the key is again depressed.

It is evident at a glance that the moment the foot of the jack has returned to the position shown in fig. 2, so that it partially rests on the fixed but E, all the parts being in the positions shown in fig. 2, the hammer not having fallen beyond the edge of lip e', and the key-lever not touching either cushion c c', the slightest depression of the key will instantly raise the jack again, and strike the hammer against the string, and that this process may be repeated as often as may be desired, and as rapidly as the hammer, by the force of its weight, assisted by the action of spring S and arm L, can be thrown down from the string to the lip of the back-catch, or, in other words, so rapidly that the ear will hardly be able to distinguish between the sounds produced, however distinct and perfect each sound may be.

Should the action work at any time imperfectly, it can be readily adjusted, in every respect, by a turn of the regulating-screws which support the several parts E, C, n, l, m.

By removing the screws r r, and detaching the flanch from the rail, the hammer, stem, jack, and arm L, are separated from the instrument and may be removed together. The key-lever, with the parts E, C, D, which it supports, may then be removed by lifting it from its fulcrum.

It will be observed, that by arranging the spring S in the position shown and described, its tension will be least at the instant that the arm L is in contact

with stop l, at which point the action of the spring is to be overcome, and is greatest at the moment that the foot of the jack is about to pass from lever C to but E, when the full power of the spring is needed.

It will also be observed, that as the foot of the jack slides off of but E upon the lever C, its weight will depress the but of the latter, and raise the back-catch to meet the descending hammer. The latter will fall back upon the inclined cushion, striking it at an acute angle, so as to produce no jar or shock, and sliding quickly and easily over lip e'.

Having thus described my invention,

What I claim as new, and desire to secure by Letters Patent, is—

1. The combination of back-catch, having lip e', with lever C, pivoted, near its centre, upon the adjustable fulcrum B, and operating, in connection with stop m or fixed but E, substantially as and for the purposes specified.

2. The spring S, when applied between the flanch and flanch-rail and the front side of a jack articulated at the stem G at j, substantially as and for the purposes specified.

3. The arm L attached to the jack J, and operating in connection with stop l, substantially as and for the purposes described.

4. The adjustable stop n, supported by a post attached to the but E, or key-lever, and operating in connection with the jack, substantially as and for the purposes indicated.

To the above specification of my invention, I have signed my hand, this 24th day of April, 1869.

A. W. PERRY.
